UNITED STATES PATENT OFFICE.

THOMAS ELLIOTT, OF DALLAS, OREGON.

BAND-CUTTER AND FEEDER.

SPECIFICATION forming part of Letters Patent No. 660,632, dated October 30, 1900.

Application filed August 5, 1899. Serial No. 726,303. (No model.)

To all whom it may concern:

Be it known that I, THOMAS ELLIOTT, a citizen of the United States, residing at Dallas, in the county of Polk and State of Oregon, have invented a new and useful Band-Cutter and Feeder, of which the following is a specification.

This invention relates to band-cutters and feeders; and the objects in view are to provide means for effectively cutting the bands and properly dividing the sheaf and feed the upper portion considerably faster than the under part, to avoid choking of the cylinder and concave of the thresher, and thereby render the operation of the thresher much more advantageous and thorough, to afford convenient means for changing the speed of the running parts, to accommodate different operations and under varying conditions, and to supply adjustable features to facilitate reduction of the longitudinal dimension of the device and its arrangement over the end of the thresher, to which it is attached in folded position.

Other objects and advantages will appear in the subjoined description, and the novel features will be set out in the claims, the preferred embodiment of the invention being illustrated in the accompanying drawings, wherein—

Figure 1 is a side elevation of the improved band-cutter and feeder shown applied to the end of the thresher in operative position and also folded over in dotted lines to reduce the device to compact form when not in use. Fig. 2 is a top plan view of the improved band-cutter and feeder. Fig. 3 is a central longitudinal vertical section of the feeder and part of the thresher as shown arranged in Fig. 1. Fig. 4 is a detail perspective view of a part of the feeder. Fig. 5 is a detail view, in sectional elevation, of friction mechanism for driving the lower draper and relative parts.

Similar numerals of reference are employed to indicate corresponding parts in the several views.

The numerals 1 and 2 designate contiguously-arranged sections hingedly connected by a transversely-extending pintle or rod 3, fitted in coinciding ears 4 and 5, respectively projecting from the upper terminals of ver-

tical straps 6 on the inner end of the section 1 and horizontal straps 7 at the upper opposite edges of the section 2. At the outer end 55 of the section 1 is a transverse shaft 8. At the inner lower portion of the section 2 is a similar shaft 9, and on opposite extremities of the said shafts are small sprocket-wheels 10, to operatively receive the links of chain belts 60 11 of a lower draper 12, having slats 13 extending transversely thereof at regular intervals, provided with teeth 14, extending outwardly therefrom and curved rearward reversely to the direction of the plane of movement of the said draper to feed the lower part of said sheaf with a drag or slower than the upper portion. The shafts 8 and 9 are located at opposite end portions of the bottoms 15 and 16, respectively, of the sections 1 70 and 2, the shaft 8 being longitudinally adjustable and having movably attached thereto a shifting bottom plate 17, which conjointly acts with the bottom 15 of the section 1 to serve as an extension of the bottom 16 of the 75 section 2 or as an intermediate partition between the opposite portions of the draper 12, which move therearound. The movement of the draper 12 is regular, and that portion thereof which travels above the bottom 15 80 and 16 and the plate 17 is closer to the latter parts to prevent too great sagging or depression of said portion of the draper and also insure a close feed of the grain to parts which will be presently set forth.

The opposite sides 18 of the section 1, adjacent their rear ends, are formed with longitudinal slots 19, having rear lower bearing-recesses 20 to receive the opposite extremities of the shaft 8 and to hold the shaft down in 90 the recesses. When the parts are arranged in operative relation, pivoted arms 21 are employed and connected to the said sides 18 by pins 22, having eyes 23. On the rear ends of the arms 21 bearing-caps 24 are secured and 95 formed with upwardly-projecting curved bearing-seats 25, the lower faces of the said caps having friction-clasps 26, secured at one end thereto. The said keepers are preferably constructed in the form of plate-springs, 100 having their inner ends attached to corresponding ends of the caps 24 and the outer ends extended to provide operating-terminals 27. That part of each clasp which extends

across the bearing-seats 25 is similarly struck up, as at 28, and stands clear of the said seat, so as to afford sufficient yielding movement to establish a resilient fastening to hold the 5 said arms 21 down in locked position against accidental disengagement and with sufficient resistance to overcome such tendency due to the operation of the shaft 8. The caps also have a yielding pressure on the opposite portions of the shaft 8 through the medium of the clasps, and when the arms 21 are down in locking position they cover the slots 19 and prevent the passage of loose grain outwardly therefrom. By having the shaft 8 adjustable 10 and movable in the slots 19 the draper 12 can be slackened and the section 1 permitted to be thrown up over the section 2 without injury to said draper. When the shaft 8 is moved inwardly in the slots 19, the plate 17 slides 15 over the upper outer portion of the bottom 15, and in releasing the said shaft for this adjustment the clasps 26 are disconnected by releasing them from frictional pressure and the arms 21 thrown up, as clearly shown by 20 Fig. 4, to uncover the slots 19. The improved device can by the means specified be reduced to compact form in a convenient manner and without injury to the draper 12, and, furthermore, the benefit ensuing from 25 an intermediate partition in a horizontal plane between the upper and lower portions of the draper 12 in the section 1 can be preserved.

Around the outer terminal of the section 1 and embracing the top and sides is a band 35 28^a, preferably formed of suitable strap metal and connected to the outer end of the longitudinally-disposed central guide 29, which has its inner extremity likewise attached to a similar band 30. The lower edge of the guide 29 40 is located so far above the plane of movement of the teeth 14 of the draper 12 as not to interfere with the operation of the latter, and at its outer end said guide centrally extends to an inclined feed board or plate 31, which 45 also has its lower edge elevated to clear the draper 12. The inner extremities of the sides 18 of the section 1 are widened, as at 32, the said increased dimension beginning from the point of location of the band 30 and extending 50 to the outer end of the section 2. Extending transversely across the section 1 and having bearings at its opposite ends in the widened extremities 32 of the sides 18 is a shaft 33, located adjacent the band 30 and having fixed thereon at regular distances apart 55 a series of band-cutting disks 34, which are obliquely arranged to effect a shear-cut and are held in regular relation by interposed spacing-sleeves 35, fitted on the said shaft.

60 One end of the shaft 33 is projected beyond the adjacent side of the section 1 and has a band wheel or pulley 36, keyed or otherwise fastened thereon and surrounded by a belt 37, running from a band wheel or pulley 38, 65 fast on the projected end of a shaft 39, having bearing in the upper outer portions of the opposite sides 40 of the section 2. At the in-

ner portions of the said sides of the section 2, in parallel relation to the shaft 39, a shaft 41 has bearing, and on both shafts 39 and 41 70 sprocket-wheels 42 are keyed and surrounded by chain belts connected to an upper draper or feeding-apron 43, also having cross-slats 44 at regular intervals, with teeth 45, curved in the direction of movement of the said draper 75 or apron 43 and reversely to the teeth 14 on the draper 12. To prevent sagging of the draper 43 and maintain a regular distance between the inner part of the draper 12 and that portion of the draper 43 which moves 80 thereover, longitudinal guards 46 are secured to the inner faces of the sides 40 of the section 2 to permit the chain belts or other devices connected to the draper 43 to be guided and sustained in a substantially horizontal 85 plane.

The shaft 41 is extended outwardly from the side of the section 2 opposite to that from which the shaft 39 is projected, and thereon is secured a cone or double pulley 47, having 90 an outer enlarged band-engaging portion and an inner smaller band-face. The shaft 9 is extended at both ends beyond the opposite sides of the section 2, and the extended end thereof nearest the extended end of the shaft 95 41 also has a cone or double pulley 48 thereon, with two belt-faces. The outer portion of the pulley 48 is double the diameter of the similar part of the pulley 47, and a similar proportion exists between the inner parts of 100 said pulleys, the larger dimensions being in the pulley 48. On the opposite extended end of the shaft 9 is a pulley 49, surrounded by a belt 50, running from the driven device 51 on the thresher to which the improved device 105 52, which is applied. Friction mechanism 52, which will be more fully hereinafter set forth, is supported adjacent the pulley 49 and partially located on the shaft 9. A frame 53 surrounds the extended end of the shaft 9, 110 bearing the pulley 49, and affords a bearing for said shaft end. The friction-mechanism-operating devices are also connected to the frame 53, and the function of said devices is to slow up or slacken the speed of the shaft 115 9 and the draper 12. It will also be observed that the speed of rotation of the shaft 41 will be considerably in excess of that of the shaft 9, and consequently the draper 43 will travel much faster than the draper 12, and to impart the motion of the pulley 48 to the pulley 47 a crossed belt 54 is used.

The shaft 9 is intended to be located at a suitable distance from the teeth of the cylinder of the threshing-machine to which the 125 device may be applied, and immediately below the said shaft is an inclined feed-chute 55, having a flat bottom adapted to be closely arranged to the cylinder and concave of the thresher. The inner end of the section 2, 130 which is disposed in the thresher adjacent the cylinder and concave, is also provided with a hinged hood 56, that drops to a point sufficiently low to shield the working parts in the

section 2 and overcome any interference of the blast or other air-currents in the thresher with the operation of the drapers 12 and 43. The hood 56 can be elevated at any time to expose the mechanism in the adjacent part of the section 2 for the purpose of repair or other manipulation. The outer reduced end of the chute 55 is open to serve as an air-feed and is held rigid by a cross-rod 57, secured in opposite hangers 58, and depending from opposite sides of the section 2 are skeleton brace-frames 59, having their inner vertical members, that may be at times rested against the end timbers of the thresher. Rests 60 project outwardly from the frame 59 and contact with the under opposite portions of the inner end of the section 1 when the latter is in operative position. As a further means of holding the section 1 in horizontal working position legs 61 are secured to the opposite sides 18, about midway of the latter, and have a series of apertures 62 therein to receive the ends of brace-rods 63, movably attached to the eyes 23 of the pins 22. The function of these legs is well understood, and when the section 1 is folded over on the section 2, as shown by Fig. 1, the braces 63 are disconnected from the legs 61, and the latter are adapted to be turned up against the opposite sides of said section 1 through the medium of a pivotal connection, as at 64. Binding-straps and other braces will be applied where necessary, and as a convenient means of adjusting the shaft 8 the opposite ends are extended beyond the sides 18 of the section 1. The shaft 33 for the disk-cutters 34 is preferably square, and the openings through the said cutters and the sleeves 35 are of similar contour, with obvious advantages.

The bound sheaves are thrown lengthwise on the feed board or plate 31, on opposite sides of the guide 29, and are caught by the teeth 14 of the slats 13 on the draper 12 and by the movement of the latter fed under the cutters 34, where the bands are severed and the loosened grain spread transversely on the said draper and in this condition carried under the upper draper 43 and thence falls onto the bottom of the chute 55, and subsequently between the cylinder and concave of the thresher. It will be observed that the arrangement of pulleys on the shafts 9 and 41 is to effect a slower action or travel of the lower draper 12 than the upper draper 43. It has been found that the best results are derived by having the speed of movement of the lower draper only about one-half as fast as the upper draper, and consequently when the grain is brought under the upper draper the more rapid movement of the latter will quickly feed off or separate the upper part of the sheaf from the lower part, and thereby ease the driving power and give the thresher, particularly the separator mechanism thereof, more time to effectually carry on its work with much less stress. This operation is facilitated by the direction of the teeth 14, which do not feed with a direct pull on the grain. The obliquity of the cutters 34 will also greatly assist in the operation of the upper draper by dividing the sheaf as it passes thereunder. By slowing the under draper and increasing the speed of the upper one the upper draper feeds with the same speed, but much less straw, as the under draper moves slower and holds the under part of the sheaf, as previously indicated.

The friction mechanism 52 is composed of a longitudinally-disposed short fixed shaft 64^a, held in the opposite ends of the frame 53 close to the extended end of the shaft 9. On said shaft 64^a are loosely mounted friction-rollers 65, which are located in front and rear of the extended end of the shaft 9 and connected to shoes 66 and 67. Movably attached to the shoe 66 is a link 68, and in like manner to the shoe 67 a link 69 is secured. The link 69 is shorter than the link 68, and the shoe 67 is in reverse position to the shoe 66, and both links 68 and 69 are movably connected to the shifting-lever 70, pivotal, supported on a fulcrum projection 71 from the end of the frame 53 adjacent the separator. The lower end of the shifting-lever 70 is provided with a grip or handle 72, and near the latter is a dog 73, which is located near and in relative position to an arm 74, provided with a series of teeth 75. The pulley 49 is loose on the extended end of the shaft 9 and is maintained in a certain outward position on the said shaft-extremity by a collar 76, which bears against adjacent portions of the side of the frame of the band-cutting and feeding attachment. On the outer extremity of the extended end of the shaft 9 a friction-disk 77 is fixed, and the friction-rollers 65 are located between the opposing faces of the said pulley 49 and disk 76, the contact of all of said parts being invariably maintained through the medium of an initial interval arrangement. It will be observed that the operation of this friction-disk will be as follows: Motion from the driving device 51 of the thresher or separator will be transmitted by the belt 50 to the pulley 49 and from the latter through the friction-rollers 65 to the disk 77 and through the latter to the shaft 9. This arrangement provides for the connection of all irregular movements or fluctuations of the driving element 51, and by shifting the rollers 65 on the shaft 64^a the speed may be varied to regulate the movement of the drapers, and to secure a more positive action of these parts the belt 54 is crossed. If the rollers 65 are simultaneously moved by the devices connected thereto toward the center of the pulleys 49 and friction-disk 77, the motion of the shaft 9 will be faster than when the said friction-rollers are nearer the peripheries of said pulley and friction-disk, and an adjustment can thus be obtained having a wide range and to accommodate various kinds of grains fed into the band-cutter and feeder. The shaft 64^a has an intermediate bend 78 to

pass the under or extended end of the shaft 9 and to bring the friction-rollers 65 in central contact with the pulley 49 and the disk 77 or in horizontal diametric position to more effectively carry out the intended result.

Changes in the proportion, size, and the minor details of construction can be resorted to without departing from the principle or sacrificing any of the advantages of the invention.

Having thus described the invention, what is claimed as new is—

1. In a band-cutter and feeder, the combination of two sections, one hinged to the other, 15 a shaft in each section to operate a lower draper, the shaft in the hinged section being longitudinally movable in elongated slots in the opposite sides of the latter to regulate the tension of the draper, a horizontally-disposed 20 shiftable partition secured to the said longitudinally-movable shaft and located between the upper and lower parts of the lower draper, arms attached to the opposite sides of the hinged section to close the slots therein and 25 having caps to engage the opposite ends of the adjustable shaft, and a series of rotary disk cutters in the hinged section above the lower draper.

2. In a band-cutter and feeder, the combination of inner and outer sections pivotally connected to each other, a shaft in each section, the shaft in the outer section being adjustable longitudinally, a lower draper operated by said shafts, a horizontal partition between the upper and lower parts of the said draper having a rear longitudinally-shiftable portion attached to the adjustable shaft in the outer section, an upper draper completely located in the inner section which is fastened 40 to the threshing-machine, a series of rotatable disk cutters in the outer section above the lower draper, said cutters being arranged diagonally to the direction of movement of the said lower draper and a longitudinally-disposed central guide in the hinged section extending from the rear portion of the latter to the disk cutters, the lower edge of the said guide being elevated above the plane of the upper portion of the lower draper.

3. In a band-cutter and feeder, the combination of two sections, one hinged to the other, a shaft in each section, the shaft in the hinged

section being adjustable longitudinally, a lower draper operated by said shafts and extending longitudinally through the greater 55 portion of the lower part of both sections, a horizontal partition between the upper and lower parts of the said lower draper having a shiftable portion attached to the longitudinally-adjustable shaft, means for slackening 60 or tightening the said lower draper, a longitudinally-disposed central guide extending from the rear portion of the hinged section forwardly over and above a part of the draper, a series of rotatable disk cutters in the hinged 65 section adjacent the front terminal of the said guide and disposed above the plane of the lower draper and operating diagonally of the direction of movement of the said draper, an upper draper situated completely within the section passing through the threshing-machine, located over the forward portion of and having a greater speed than the said lower draper, both drapers in operative position being in parallel planes, and means for regulating the 70 speed of the drapers.

4. In a band-cutter and feeder, the combination of feeding-drapers arranged in parallel relation one above the other, driving power for said drapers, and friction mechanism connected to said driving power and one of the shafts of the lower draper and consisting of a pulley loose on the shaft of the draper, and a friction-disk fast on the same shaft, and friction-rollers interposed between the said 85 pulley and disk.

5. In a band-cutter and feeder, the combination of upper and lower drapers, the lower draper having an extended shaft, a fixed shaft extending in a plane at right angles to the 90 said extended shaft, friction-rollers shiftable mounted on the said shaft at an angle to the extended shaft, a pulley loose on the extended shaft, and a friction-disk fast on the same shaft, the said friction-rollers being interposed between the disk and pulley, and a driving device applied to the said pulley.

In testimony that I claim the foregoing as my own I have hereto affixed my signature in the presence of two witnesses.

THOMAS ELLIOTT.
